L. M. ADAMS,
TYPOGRAPHIC PLATE,
APPLICATION FILED SEPT. 16, 1919.

1,346,583.

Patented July 13, 1920.

UNITED STATES PATENT OFFICE.

LEWIS M. ADAMS, OF RIDGEFIELD PARK, NEW JERSEY.

TYPOGRAPHIC PLATE.

1,346,583.

Specification of Letters Patent. Patented July 13, 1920.

Application filed September 16, 1919. Serial No. 324,185.

To all whom it may concern:

Be it known that I, LEWIS M. ADAMS, a citizen of the United States, residing in Ridgefield Park, county of Bergen, State of New Jersey, have invented certain new and useful Improvements in Typographic Plates, of which the following is a specification.

This invention consists in a novel method 10 of producing printing plates or other units for printing or for the formation of matrices, or for other special purposes, and the novel plate or unit thereby produced. An object of the invention is to cheapen and expedite the manufacture of such plates or units.

The invention in general may be practised by welding, fusing or soldering or otherwise uniting separate type elements 20 into an integral plate of convenient thickness for "lock-up" in press, or into a unit of any desired shape and size for use in printing or forming matrices as well as for other special purposes. The type elements thus 25 to be integrated may consist in a page of linotype slugs, movable type, or any type composed in a page of any size or form.

The practice of the invention in the production of flat plates, is illustrated in the accompanying drawings, in which:

Figure 1 shows a side sectional view of the frame in which the process is carried out, the linotype slugs being shown in place in the frame, and the plane of section being 35 taken on the line 1—1 of Fig. 2;

Fig. 2 is a plan view of the frame with linotype slugs in place and hack saw ready to begin the cut for thinning the plate;

Fig. 3 is a sectional view on the line 3—3 40 of Fig. 1, showing a modified form of frame having bevels and grooves cast or cut in the plate;

Fig. 4 is a sectional view corresponding to Fig. 1 but showing a modification in which 45 the frame is formed of two upper and lower portions hinged together to facilitate the fusing operation.

This process produces from a page comprising a plurality of separate type units, 50 an integral plate which is thinner and contains less metal than the original units, thus making its long preservation more economical, and permitting its use in the manner of and in the place of stereotype or electrotype

plates. The integral plate thus produced 55 may be thinned if desired to standard or any other special thickness and then beveled or grooved for facilitating its "lock-up" in a press. In the appended claims the word bevel will be employed to generically designate a simple bevel or groove, or other equivalent.

Three of the specific ways of carrying out this invention may be designated as follows:

1. As shown in Fig. 1 the type is locked in 65 a special frame or chase with a slot so disposed that a saw or electrically heated nicrome wire or other severing means working in the slot, can cut off the bottom part of the type. In practice I have removed 70 about $\frac{1}{8}$ inch from the total height of type (generally $\frac{1}{4}$ inch) by this means. A hot iron or plate or flame is then applied to the back surface of the upper half of the type, fusing welding or searing the linotype slugs 75 or other type elements into an integral plate. This plate then is planed and trimmed to the desired size. If desired the type may be cast so that there is a bevel in the plate for lock-up in the press. This bevel may be 80 trimmed or not. Or a bevel or groove may be cut in the plate for this purpose, after the plate has been formed as shown in Fig. 3. When the bottom or back ends of the type are severed by the fusing action of a 85 hot wire as aforesaid, the searing action of the wire may alone suffice to leave the type fronts integrated without the additional heating and fusing operation.

2. According to the second method heat 90 may be directly applied to the bottom of the type page in the frame, melting away the metal until the required thickness is attained, and by this action or by a supplemental heating the type elements will be sufficiently 95 fused into an integral plate, and then finished as above.

3. According to the third specific illustration of the practice of this invention, heat may be applied directly to the bottom 100 of the type #2, and may be maintained for a relatively long time, fusing it into a plate, while holding all the metal in the frame. This makes a solid plate practically as thick as the height of the type, which may then 105 be planed and trimmed and beveled, as desired.

After the plate has been formed by any of

the foregoing methods, it may be electrolytically or otherwise coated in any well known manner with steel, nickel, copper, or other suitable metal, either for preservation 5 or any other special purpose.

To assist in cooling the front or typed face during the fusing or severing operation, this face may be placed in contact with a metal plate or other material for drawing off 10 the heat, or a stream of air or liquid may be passed across it. For instance an electric fan may be arranged to blow upon it.

Referring to the drawings:

1 is the frame or chase in which the type 15 are held for cutting and fusing. The type units 3 may be locked in this frame with their faces pointing downwardly and with the backs of the type unit at the top. This may be done in any convenient way, as by 20 set screws or by quoins. The figure shows the use of conventional blocks 4 and quoins 12. When it is desired to thin the plate in the frame, these blocks and quoins may be, as shown, thinner than the frame and disposed above and below the cutting slots 2, so as to avoid the saw 5. These blocks and quoins could of course be the full thickness 25 of the type 3, and be severed by the cutting means as the type is severed. The design 30 in Fig. 4 is particularly adapted to this application. In practice the quoins will probably not be severed, the end quoins being constructed in divided form to allow the saw to pass, and the side quoins being 35 either similarly divided, or else being removed during the cutting operation. In the construction of Figs. 1 and 2 either the quoins or blocks, or both, at the end of the frame where the saw is started, must be 40 made in upper and lower parts to provide a starting slot for the saw.

In Fig. 4 the frame is shown so arranged that the severing means may be more easily introduced, and so that its upper half may 45 be hinged back or removed after the severing operation to facilitate the application of heat and the introduction of planing and trimming tools. While the type is being locked in, the two halves of the frame will 50 be held at one end by the hinge 10, and at the other end by the bolts 7, thumb nuts 8, and the removable bar or washers 9, on the extensions 6. Once the type is securely fastened these nuts, bolts, and washers (or 55 bar) may be taken out to permit the introduction of the saw or other severing means, while said severing means is held at both ends in a suitable frame or other carrying device. Removal of these bolts and 60 washers may also be necessitated by the use of a severing means with blade too wide to enter slot when they are in place. After the type has been cut the upper half of the frame may be hinged back to permit 65 fusing, planing, and trimming.

Obviously any manner of integrating the type elements may be adapted to the practice of the broad idea, whether the elements be welded by fusing their own metal, or integrated by adding solder or by utilizing any other means that produces a cohesive or adhesive juncture. 70

As shown in Fig. 3 bevels 13 may be employed to assist in "lock-up" in press. These may be cast or cut in the separate 75 type, or cut or otherwise made in the plate when formed. They are most clearly seen in Fig. 3.

In the appended claims the term cohesion will be used generically to cover both cohesion and adhesion in their narrow and opposed senses, since it is now generally considered good form to describe the intimate molecular juncture both of dissimilar bodies and of similar bodies under the general head 85 of cohesion.

It is obvious that various modifications may be made in the procedure and construction shown in the drawings and above particularly described, within the principle and 90 scope of my invention.

I claim:

1. The process of forming an integral type unit which consists in assembling separate type elements and uniting them by 95 cohesive junctures, the back surface of said integral type unit being completely integrated.

2. The process of forming a printing plate which consists in assembling separate type 100 elements and fusing them together, the back surface of said plate being fused into an integral mass.

3. The process of forming an integral type unit which consists in assembling separate type elements, removing bottom portions thereof, and cohesively integrating the 105 entire back or bottom surfaces of the remaining portions of said type elements.

4. The process of forming an integral 110 type plate which consists in assembling separate type units, removing the bottom portions thereof, and fusing the remaining portions into a plate unit by the application of heat to their back surface, the back surface 115 of said plate unit being fused into an integral mass.

5. The process of forming an integral type plate which consists in assembling type 120 elements, and cohesively integrating them by means requiring the use of heat while holding their typed face in contact with a cooling medium.

6. The process of forming a printing plate which consists in assembling type elements, cohesively integrating them by means 125 requiring the use of heat, and cooling their typed face by bringing it into contact with a metal plate.

7. The process of forming a printing 130

plate which consists in assembling type elements, fusing them, and holding their typed face in contact with a cooling medium.

8. The process of forming a printing plate which consists in assembling type elements, fusing them, and holding their typed face in contact with a metal plate.

9. A type plate for printing comprising a plurality of thinned linotype slugs, the edges of each of the slugs of said type plate being fused together to form a plate

having an integral back or bottom surface.

10. The process of forming a type column which comprises clamping a plurality of linotype bars with their type faces in the same plane, and fusing the adjacent back surfaces of said bars to each other into an integral body of metal.

In testimony whereof I have affixed my signature to this specification.

LEWIS M. ADAMS.
